UNITED STATES PATENT OFFICE.

JOHN D. BLOOM, OF NEW YORK, N. Y.

COMBINED BLACKING-BRUSH, BLACKING-HOLDER, AND DAUBER.

SPECIFICATION forming part of Letters Patent No. 791,867, dated June 6, 1905.

Application filed May 17, 1904. Serial No. 208,365.

To all whom it may concern:

Be it known that I, JOHN D. BLOOM, a citizen of the United States, and a resident of New York, in the county of New York and State of New York, have invented certain new and useful Improvements in a Combined Blacking-Brush, Blacking-Holder, and Dauber, of which the following is a specification.

This invention relates to that class of blacking-brushes wherein the brush-back contains a well or pocket for the reception of blacking, said back being also provided with a longitudinal recess for the accommodation of the handle of a dauber, so that the combined article thus presented is of compact form, convenient for portability, and capable of ready disassociation when required for use.

The object of the present invention is to simplify and render more efficient the construction of such type of combined articles and to so condition the bristle-carrying part of the dauber with relation to the contiguous portion of the brush proper, that when the dauber is compactly disposed with relation to the brush proper, the blacking-applying part of said dauber will be in a plane different from that of the ends of the brush-bristles, so that liability of the dauber objectionably smearing or imparting the blacking to the brush-bristles will be avoided to a considerable extent.

With the above and other purposes in view the improvement comprehends a blacking-brush the back of which has a recess at one end, said back also containing a longitudinally-disposed shallow depression, leaving parallel side projections and a transverse limiting projection contiguous to the other end of the back, the said side and transverse projections being undercut to permit the beveled side and end edges of a thin dauber-handle to slidingly engage beneath said projections to retain the dauber in its relation with the bristle-carrying portion of the dauber occupying the recess at the end of the back of the brush proper, the ends of the dauber-bristles, when the dauber is so confined, being in a longitudinal plane nearer that of the back than that of the brush than those of the brush proper, whereby the dauber-bristles are prevented from smearing. Immediately in the handle-depression is a circu-

lar well or pocket for the reception of blacking, which well is completely covered when the dauber-handle is slid in engagement with the back.

There are other important features connected with the invention, which, besides those alluded to, are clearly set forth in the subsequent detailed description.

In the accompanying drawings, forming part of this specification, Figure 1 is a plan view of a blacking outfit embodying my invention. Fig. 2 is a central longitudinal section of the outfit as it appears in Fig. 1. Fig. 3 is a transverse section of said outfit, the plane of section being that indicated by the broken line 3 3, Fig. 2. Fig. 4 is an end view of said outfit. Fig. 5 is a plan view of the brush proper, the dauber being removed.

Similar reference characters are employed to designate corresponding parts in the several views wherein they occur.

The brush proper embodies the comparatively thick back A, at the under side of which is secured the plate B, carrying the bunches of bristles b. At its upper side the back A has a shallow longitudinally-extended recess a, which is defined on three sides by the parallel ledges a' and end ledge a''. At one end the back has a recess A', which intersects the recess a.

At an intermediate point and somewhat contiguous to the recess A' the back has a circular well or pocket C for the reception of a box of blacking. This well or pocket can be formed by boring or cutting out the back before the latter has the bristle-carrying plate attached thereto.

The dauber comprises the thin flat handle D, which is adapted to be slid and be retained beneath the ledges a' a'', which are undercut to receive the beveled side and end edges of the dauber-handle. One end of this latter overhangs the end recess of the brush-back. Secured on the under side of the overhanging part of the handle D is a block d, carrying the brushes of bristles d' of the dauber. It will be observed by reference to Figs. 2 and 4 that the dauber-bristles d' terminate short of the lower ends of the bristles b of the brush proper. Consequently the end recess of said

back admits of the snug reception of the bristle-carrying portion of the dauber, while the clearance of the dauber-bristles admits of the brush being placed to rest on its bristles 5 without the liability of the dauber-bristles coming in contact with the surface on which the brush rests.

It will be appreciated from the foregoing that the combination article is not only exceedingly simple in construction and highly convenient, but it can be compactly arranged and stored in a cleanly manner.

Having now described my invention, what I claim as new, and desire to secure by Letters 15 Patent, is—

In a combined brush, blacking-holder and dauber the combination with a solid back having a vertical recess in one end on both sides of which the bristles extend forming a verti-

cal recess in continuation of that in the back, 20 a well at the rear of said first-mentioned recesses and a shallow longitudinal recess in the top communicating with said well, of a dauber provided with a handle adapted to slide into the longitudinal recess and having bristles on 25 one end adapted to slide into the vertical recess formed by the recess in the back of the brush and the recess between the bristles thereof, the ends of the bristles of the dauber coming above the ends of those of the brush, substantially as described.

Signed at New York, in the county of New York and State of New York, this 15th day of April, A. D. 1904.

JOHN D. BLOOM.
